UNITED STATES PATENT OFFICE.

FRANK HINMAN PIERPONT, OF HORLEY, COUNTY OF SURREY, ENGLAND, ASSIGNOR
TO LANSTON MONOTYPE MACHINE COMPANY, OF PHILADELPHIA, PENNSYLVANIA,
A CORPORATION OF VIRGINIA.

PUMP.

1,061,562.

Specification of Letters Patent. Patented May 13, 1913.

Application filed March 4, 1912. Serial No. 681,425.

To all whom it may concern:

Be it known that I, FRANK HINMAN PIERPONT, a citizen of the United States, temporarily residing at Salford, Horley, in 5 the county of Surrey, England, have invented a certain new and useful Improvement in or Relating to Pumps; and I do hereby declare the following to be a full, clear, and exact description of the same, reference being had to the accompanying drawings, forming part of this specification, and to the figures and letters of reference marked thereon.

This invention relates to pumps for type 15 casting machines and refers particularly to pumps which are intermittently connected with or applied to the type mold.

The nozzle through which the molten metal is delivered to the mold is usually 20 tapered or pointed and therefore lends itself to rapid cooling, hence it frequently happens that in the interval between the casting strokes of the pump the metal solidifies in the nozzle and the pump is rendered inoperative. Further, metal overflows at the 25 tip of the nozzle and solidifies there, thus preventing the nozzle seating perfectly against its seat in the mold. It is the chief object of this invention to minimize or 30 eliminate entirely these drawbacks.

According to the present invention, the pump nozzle is provided with one or more channels, chambers or jacketed portions through which some of the metal which is 35 forced up by the pump piston is passed or circulated in such a manner as to warm up or heat the nozzle and thereby prevent metal solidifying on the outer side thereof or in the main ejecting channel. The re- 40 turn outlet from the channels, chambers or jacketed portions may be controlled conveniently by a valve or tap.

The invention will be described as applied to a pump nozzle of well known form, 45 it being understood that the invention is by no means restricted to this or to any particular pump nozzle.

In the accompanying drawings illustrating a preferred form of embodiment—the 50 figure represents a vertical section of a pump nozzle containing said invention.

A is the discharge branch leading from the pump barrel.

B is the nozzle, and C a controlling tap.

The nozzle B in the present example is 55 formed in two parts one of which b is screwed, or it may be otherwise secured, in the outlet of the discharge branch A of the pump. The other part b' which forms the nozzle proper, or that part which is seated against 60 the mold opening and is provided with the discharge outlet b², is screwed or otherwise secured to the part b so that between these two parts b and b' there exists a space or chamber B'. The part b is provided with a 65 channel b³ communicating at its lower end with the bore a in the branch A, and the outer end of this channel b³ discharges into the space B' in line with and contiguous to the jet opening b² in the part b'. As indicated in the drawings the area of b³ is greater than that of the jet opening b².

Leading from the lower portion of the chamber B' is a conduit or a convenient number of conduits B² which serve for the 75 return or discharge of metal delivered into the chamber B'.

On the delivery stroke of the pump the metal is forced up through the channels a, b³, and out by the jet opening b² into the 80 mold in sufficient quantity to fill the mold and with sufficient pressure to produce solid type. The superfluous metal delivered by the pump passes into the space or chamber B' thereby imparting heat to the nozzle, 85 and this metal is returned from the chamber B' by the passage or passages B² back to the metal pot. The extra heat imparted to the nozzle by this metal prevents it cooling down to an extent which might permit 90 metal to solidify in the nozzle or on the outer walls thereof as aforesaid.

C is a tap or cock inserted in the return passage B³ by which metal from the chamber B' is returned to the metal pot, and by 95 turning the handle C' of this tap, the flow of the metal from the chamber B' back to the metal pot can be regulated at will. For convenience the cock C may be provided with a pointer C² acting in conjunction with 100 the scale or index C³ to facilitate a ready adjustment of the opening of the cock.

What I claim is:

1. A nozzle for metal injecting pumps provided with a jet opening, a metal supply passage terminating in rear of the jet opening to form a chamber in rear of said jet opening, a discharge passage for said

chamber, and an adjustable valve in said discharge passage for varying or adjusting the rate of discharge therethrough.

2. A nozzle for metal injecting pumps, 5 the same comprising a hollow conical seating section provided with a jet orifice at its apex, and a main or body section provided with attaching means at one end, a central passage and a reduced discharge 10 end, the latter located within the seating section to which it is attached at the base

to provide a metal receiving chamber within the seating section surrounding the discharge end of the main section, the latter also provided with a discharge passage communicating with said metal receiving chamber.
